UNITED STATES PATENT OFFICE

DELBERT H. FRENCH, OF OAK PARK, ILLINOIS, ASSIGNOR TO JULIUS Q. GILL, OF PEORIA, ILLINOIS

METHOD OF RECONSTRUCTING LOCOMOTIVE DRIVING JOURNAL BOXES

Application filed September 19, 1927. Serial No. 220,351.

This invention pertains to a method of reconstructing worn out discarded railway locomotive journal boxes, and the method pertains particularly to the procedure of reconstructing locomotive journal boxes of the arched type.

An object of the invention is to salvage a discarded journal-box that has become so worn as to be of no further use, by the process of machining the surfaces thereof to true them as well as to rebore them for new "brasses" or bearing parts, and to attach permanently to said box a so called "filler-block" for supporting said brasses.

Another object of the invention is to machine each inner surface of a journal-box and weld thereto a "filler-block" for carrying new brasses.

Still another object is that of machining certain surfaces of a journal-box to create a shoulder on each of two facing surfaces thereof and then weld a filler-block to each said surface supporting the same on the said shoulder.

In order that my method may be fully understood I have provided the accompanying drawings forming part hereof which show one of the types of journal-box in general use, the result of its treatment, and the finished article.

Figure 1 is a front elevation of a journal-box of a well known type.

Figure 2 is a similar view showing the box reconstructed as to outline within the arched opening thereof, together with parts added according to my invention.

Figure 3 is a transverse sectional elevation of the journal-box as produced on line 3-3; Figure 2.

Figure 4 illustrates in perspective a portion of the journal-box shown in Figure 2, and

Figure 5 illustrates in perspective a portion of the box and filler-block and the method of securing the latter to the former.

In my pending patent application for a journal bearing filed in the U. S. Patent Office May 28th, 1926, under Serial No. 112,221 there is illustrated and described the article, a journal-box, together with a filler-block for

attachment to the same. This present invention relates to the manner of treatment of the box and the method of securing the filler-block by welding.

When a journal-box has become so worn as to be unfit for use I am enabled to reconstruct it so that it is good for many thousands of miles of service while at the same time providing advantages in the use of certain added parts having no part in the present application except to show the use and value of the filler-block and the particular manner of its attachment to the box.

In Figure 1 is illustrated a journal-box 1 as of a form in use on railways at the present time wherein it is observed that within the central arched opening thereof there are two prominences 2, and that the facing surfaces of the walls within said opening below the prominences are, in this instance, of an irregular form.

In my method of treatment of the box these said prominences 2 and the said irregular surfaces are removed by machining away the metal substantially along the dotted lines 3, 4, 5 preferably leaving a shoulder or ledge 6 as indicated in Figure 2 which figure shows the same box machined as described, and in which, also, the numeral 7 designates a vertical surface at each side of the arched opening 8 which meets the said ledge or shoulder 6. The shoulders thus formed extend in the direction of each other and parallel surfaces 9 drop therefrom as shown all in agreement with the said dotted lines of Figure 1. Besides thus machining these surfaces the metal at the top of the arch 8 is machined to true the same with the surfaces 7, and recesses 10, Figure 3, are also created to receive certain end flanges 11 of a "crown brass" which, however, is without invention herein.

My invention lies in the removal of the metal at opposite sides of the arched opening as already described, and the attachment 95 of the filler-block designated at 12. The described treatment of the journal-box removes metal therefrom within the arched opening so that a better form of support for the "crown brass" and certain "side brasses" 100

may be provided and by which a wedge may be employed to adjust the named brasses.

The block 12 as shown in Figure 4 is substantially flat but having on one of its surfaces at what may be termed its top edge an enlargement 13 having a machined under surface 14 to lie upon the machined ledge or shoulder 6 of the box. In addition, the block has a series of holes 15 which in this instance extend through the said enlargement 13 which preferably taper from what may be termed the outer surface of the block toward the inner surface that is to lie upon the surface 7 of the box as may be seen in Figure 2. As usually constructed a journal-box has depending ears 16 to accommodate a bolt, not shown, for supporting a grease cellar closure, not shown, and the filler-block therefore has corresponding ears 17, by choice, although these are not necessarily concerned in the present invention.

The block 12 when placed in position as shown in said Figure 2 is below the axial center of the journal box and receives upon its top a wedge 18 for supporting a "quarter" or "side" brass 19 opposite the axial center of the journal box space and upon which brass rests one end of a "crown brass" 20 previously referred to. That the wedge 18 may function to raise the brasses 19 and 20 the top edge of the filler block is beveled at 21 throughout its length, as shown best in Figure 3, being also beveled laterally downwardly and inwardly toward the surface 7 of the box as at 21', Figure 2.

The block is attached or secured to the box preferably by electric or oxy-acetylene welding in substantially the following manner: The welding-metal is fused upon and attached to the surface 7 of the box within the tapering holes 15, filling the latter and to the walls of which it is also fused, the metal resulting from such operation forming a conically shaped wedge and denoted at 22. Due to the fact that the metal is thus built up upon and from the surface 7 in the wedge form, and that it is extremely hard, a very strong and permanent job results.

I may provide additional holes 23 and 50 provide further built-up metal at 24, in addition to which spot welding may be resorted to at 25 where the edges of the box and block adjoin, or the welding-metal may be built up along the entire line of separation of said box and block in lieu of or in addition to the spotting of the same.

Although the shoulder or ledge 6 and the enlargement 13 are shown to rest one on the other, these may not be used although their 60 employment is preferable as an additional support to the welded-in plugs 22 for supporting the brasses resting upon the block.

I claim:

1. In a method of reconstructing a locomotive driving journal box of the arched

type, the method which includes machining metal from the opposite facing surfaces of said box within the arched opening thereof, machining the surface of a plate to lie against the resulting machined surface of the box to have a surface complementary to the said resulting machined surface of the box, creating perforations in said plate, placing the plate upon said machined surface, and fusing metal upon the box within the perforations and filling said perforations with fused metal. 70

2. In a method of reconstructing a locomotive driving journal box of the arched type, the method which includes machining metal from the opposite facing surfaces of said box within the arched opening thereof, machining the surface of a plate to lie in intimate contact with the machined surface of the box and complementary thereto, creating perforations in said plate to open upon the box, placing said plate upon the box, fusing metal upon the box within the perforations and filling the perforations with the fused metal, and fusing metal upon both the box and the plate at the junctures of the edge of the latter with said box. 80

3. In a method of reconstructing a locomotive driving journal box of the arched type, the method which includes machining metal from the opposite facing surfaces of said box within the arched opening thereof, machining the surface of a plate to lie in intimate contact with the machined surface of the box and so that the surfaces are complementary to each other, creating conical perforations in said plate to open upon the box, placing the plate upon the box, fusing metal upon the box within the perforations and filling the latter with fused metal. 90

4. In a method of reconstructing a locomotive driving journal box of the arched type, the method which includes machining metal from the opposite facing surfaces of said box within the arched opening thereof, machining the surface of a plate to lie in intimate contact with the machine surface of the box so that the respective surfaces are complementary to each other, creating conical perforations in said plate, placing said plate upon the box with the smallest diameter of the perforations adjacent said box, fusing metal upon the latter within the perforations and filling the latter with the metal, and fusing metal at the juncture of and to the marginal edges of the box and plate. 100

5. In a method of reconstructing a locomotive driving journal box of the arched type, the method which includes machining metal from the opposite facing surfaces of said box within the arched opening thereof, machining the surface of a plate to lie in intimate contact with the machined surface of the box so that the respective surfaces are complementary to each other, creating conical per-

forations in said plate, placing said plate upon the box with the smallest diameters of the perforations adjacent said box, beveling one edge of the plate laterally downward toward the box, beveling said plate at said edge lengthwise thereof, fusing metal upon the box within the perforations and filling the latter with metal.

5 6. In a method of reconstructing a locomotive driving journal box of the arched type, the method which consists in machining metal from the upright facing surfaces of the box within the arched opening thereof, creating a shoulder on each said surface to 10 face toward the top of the arch, forming a plate to lie against the machined surface of the box and upon said shoulder, placing the plate in position on the machined surface and shoulder, and welding the respective 15 plates to their respective upright surfaces.

20 7. The method of modifying journal boxes of the arched type having crown bearing elements resting on opposite supporting ledges on the side walls thereof which method comprises removing the metal of the ledges and 25 side walls downwardly from the extreme greatest inner dimension of the upper end of the box behind the crown-piece, terminating the cut on each wall at a point above the 30 lower end of the side walls, and thereby providing a ledge on each side wall, mounting on each side wall a separate filler-block, each having an upper end edge portion of a thickness greater than the width of said ledge for 35 engagement with upper bearing elements or wedges therefor and having a lower portion thinner than the width of said ledge and having a shoulder adapted to fit on said ledge substantially complementary thereto, and rigidly 40 securing each of said blocks to its respective side wall.

45 8. The method of modifying journal boxes of the arched type having crown bearing elements resting on opposite supporting ledges on the side walls thereof which method comprises removing the metal of the ledges and 50 side walls downwardly from the extreme greatest inner dimension of the upper end of the box behind the crown-piece, terminating the cut on each wall at a point above the lower 55 end of the side walls, and thereby providing a ledge on each side wall, mounting on each side wall a separate filler-block, each having an upper end edge portion of a thickness greater than the width of said ledge for engagement with upper bearing elements or 60 wedges therefor and having a lower portion thinner than the width of said ledge and having a shoulder adapted to fit on said ledge substantially complementary thereto, rigidly 65 securing each of said blocks to its respective side wall, introducing a quarter bearing element between the crown bearing element and the said block on each side of the structure,

and introducing a wedge element between each quarter element and said block.

9. The method of reconstructing a locomotive driving journal box of the arched type having a crown bearing element and side bearing elements, which method includes removing metal from the opposite facing surfaces within the arched opening of said box, placing a plate upon each of the two resulting opposite facing surfaces of said box with 70 the arched opening thereof and so positioned that the upper edge of said plate is below the axial center of said journal box, and attaching each of the plates to its respective opposite facing surface by welding the same thereto. 75

10. The method of reconstructing a locomotive driving journal box of the arched type having a crown bearing element and side bearing elements, which method includes removing metal from the opposite facing surfaces within the arched opening of said box, 80 machining the surface of a plate to lie against the resulting surface from which metal has been removed and to have a surface complementary to the resulting opposite facing surface, placing a plate upon each of the two opposite facing surfaces from which metal has been removed and so positioned that the upper edge of each of the plates is below the axial center of said journal box, and attaching each of the plates to its respective surface 85 by welding the same thereto. 90

11. In a method of reconstructing a locomotive driving box of the arched type, the method which includes placing a plate having openings therethrough upon each of the two opposite facing surfaces of said box within the arched opening thereof, attaching each of the plates to its respective facing surface, fusing metal upon the box within the 100 openings of the plate, and filling said openings with fused metal. 105

12. In a method of reconstructing a locomotive driving box of the arched type, the method which includes machining metal from the opposite facing surfaces of said box within the arched opening thereof, machining the surface of a plate to lie against the resulting machined surface and to have a surface complementary to the resulting machined surface, and also providing openings in the plate extending therethrough, fusing metal upon the box within the openings of the plate and filling the said openings with fused metal. 110 115 120

13. In a method of reconstructing a locomotive driving box of the arched type, the method which includes machining metal from the opposite facing surfaces of the said box within the arched opening thereof, machining the surface of a plate to lie in intimate contact with the machined surface of the box, and so that the machined surfaces are complementary to each other, creating conical 125 perforations in said plate with the smallest 130

diameter of said perforations toward the machined surface of the plate, placing the plate upon the box with the smallest end of said perforations toward one of said opposite facing surfaces, fusing metal upon the box within the perforations, and filling the perforations with fused metal.

In testimony whereof I affix my signature.
DELBERT H. FRENCH.
